WINDOW REGULATOR DRIVE MECHANISM

Burton S. Floraday, Toledo, Ohio, assignor to
Detroit Harvester Company, Detroit, Mich., a
corporation of Michigan

Continuation of application Serial No. 587,761,
April 11, 1945. This application July 3, 1950,
Serial No. 171,909

1 Claim. (Cl. 268—126)

1

This invention relates to vehicle window regulators, but more particularly to regulators for use in installations in which the inside or trim panel of the vehicle body or door is out of parallelism with respect to the plane of window movement or the regulator mounting.

An object is to produce a new and improved window regulator mechanism in which the crank handle receiving shaft is arranged at an oblique angle with respect to the axis of the regulator arm.

Another object is to produce a simple and efficient regulator mechanism for installation in a body structure in which the up and down movement of the window panel is distinctly out of parallelism with respect to the inner body panel, and in such manner that the operating crank handle can be rotated without interference with the inner panel.

A further object is to produce a vehicle window regulator mechanism provided with a swinging arm and a gear sector member and in which the axis of the operating pinion as well as its actuating shaft, is out of parallel relation to the axis of the sector member and in which the pinion is arranged in an intermediate position of an imaginary quadrant the lower line of which is horizontal and passes through the axis of the sector member, thereby enabling the window panel to move in a plane at an oblique angle to the plane of movement of the operating crank handle.

In the drawings:

Figure 1 is an elevational view of a vehicle door with part broken away showing an embodiment of the present invention arranged therein;

Figure 2 is a sectional plan view of the mechanism shown in Figure 1;

Figure 3 is a vertical sectional elevational view through the door shown in Figure 1;

Figure 4 is an enlarged semi-diagrammatic elevational view of a portion of the present invention;

Figure 5 is a diagrammatic side elevation of the regulator mechanism shown on Figures 1 to 4;

Figure 6 is a view on the line 6—6 of Figure 5;

Figure 7 is a view on the line 7—7 of Figure 5;

Figure 8 is an enlarged fragmentary sectional view substantially on the line 8—8 of Figure 5 and showing the pinion tooth in elevation;

Figure 9 is a diagrammatic side elevation of a regulator mechanism similar to that shown in Figures 1 to 7 except that the operating sector is flat and does not have a dished rim portion;

Figure 10 is a view on the line 10—10 of Figure 9;

2

Figure 11 is a view on the line 11—11 of Figure 9, and

Figure 12 is an enlarged fragmentary sectional view substantially on the line 12—12 of Figure 5 and showing the pinion tooth in elevation.

Referring now to Figure 1 in particular, the present invention is illustrated in connection with an automobile door D, which comprises generally upright and sloping pillars 6 and 7 respectively defining in the upper portion of the door a window opening 8. The lower portion of the door D includes inner and outer door panels 9 and 10 respectively defining a window well 11 into which the usual glass window panel 12 is adapted to be lowered. The glass is guided in its lowered position by means of channel guide members 15 arranged within the well 11. These channels lie in prolongation with the usual sealing grooves or guides formed in the window opening.

The glass 12 is supported in a channel bar 11 which is provided medially of its length with a depending horizontal retainer 13. The retainer 13 is provided with a slot 19 for slidably receiving 25 a stud 20 secured to the outer end of an actuating arm 21 of a window regulator mechanism 22.

The regulator mechanism 22 forming the subject matter of the present invention includes a 30 mounting plate 25 adapted to be secured to the inner door panel 9. A sector gear 26 fixed on a stud 27 pivoted on the plate 25, is arranged for limited arcuate movement for operation of the arm 21, which is secured thereto. A torsion 35 spring 28 is secured at its inner end to the stud 27 within an embossed recess in the plate 25 and has its outer end fixed to the plate so that pressure is applied in an upward direction 40 to the arm 21 for counterbalancing the weight of the window.

In installations of the present type, the door construction is such that conventional regulator mechanism can not be employed. As indicated in Figure 3 the door panels 9 and 10 are curved, 45 so that the major portion of each lies entirely outside of the plane of movement of the window panel. It will be noted also that the plane of motion of the sector gear 26 and arm 21 lies parallel to the direction of movement of the window. Thus it is necessary to provide suitable operating mechanism including an operating crank, indicated in broken lines at 30 (Figures 2 and 3), operable in a plane of rotation which is substantially parallel with the inner door panel.

In order to accomplish this a drive shaft 31

is supported in a conventional friction clutch device 32 secured to the mounting plate 25 in a position permitting a drive pinion 33 carried by the shaft 31 to engage gear teeth 34 on the sector member 26. It should be noted that the drive pinion 33 is in an intermediate position of an imaginary quadrant, the lower line of which is horizontal and passes through the axis of the stud 27. This upper position of the drive pinion is important so that the operating handle on the inside of the door is in a position convenient to the operator.

Referring to Figures 3 and 4, the broken line A indicates a horizontal base plane passing through the normal center of the drive pinion 33 and lies at a right angle to the plane of rotation of the gear 26 (Figure 2). The line B indicates the angle of inclination of the shaft 31 along the vertical line C of Figure 4 to place the shaft substantially normal or at right angles to the surface of inner door panel. This positioning of the shaft and pinion 33 requires the rim portion 26' of the gear sector 26 bearing the teeth 34 to be dished or inclined normal to the line B to facilitate engagement of the gear teeth and pinion.

Since the vertical plane indicated by line C is not in alignment with a line 35 (Figure 4) passing through the respective centers of the sector 26 and pinion 33, the teeth of the pinion are formed helically to accommodate their angular relation. This assures positive driving engagement between the pinion and sector gear.

Figures 5 to 8 show diagrammatically the relative positions of the operating parts of the regulator mechanism and the relation of the handle shaft 31 and handle crank 30 to the inside door panel. In Figure 5, it will be observed that the operating shaft 31 inclines straight upwardly and that the teeth of the pinion 33 properly mesh with the teeth of the dished rim 26' of the sector 26. In Figure 6, it will be noted that the handle crank 30 can be freely rocked without interfering with the inside door panel 9 and the shaft 31 inclines upwardly from the helical pinion 33. The proper meshing between the pinion and gear sector teeth is shown in Figure 8. Figure 7 shows the freedom afforded the handle crank 30 to rotate on the inside of the panel 9.

By way of contrast, reference is made to Figures 9 to 12 which show the same parts as described above and in corresponding positions, the only difference being that the gear sector is flat throughout and is not provided with the dished rim portion. The same reference numbers are used but with the exponent "a." The differences are apparent. The teeth of the pinion 33a do not mesh properly with the teeth of the flat gear sector 26a as shown on Figure 12. This causes rapid wear of the teeth and soon the regulator will not operate smoothly. Note the lateral angularity of the shaft 31a in Figures 9 and 11. This is objectionable because the crank handle 30a cannot be rotated due to interference of the door panel 9a.

The above graphically shows advantages gained by dishing the sector rim and using the helically toothed pinion, particularly in the illustrated location of the pinion. In fact, where the pinion is raised above a horizontal line passing through the operating sector axis, it is necessary that both dishing of the sector rim and the use of the helical pinion be employed.

This application constitutes a continuation of my application Serial No. 587,761, filed April 11, 1945, and entitled "Window Regulator Drive Mechanism," now abandoned.

While I have shown and described one embodiment of the invention which is the best form known to me at this time, it is to be understood that numerous changes in details of construction, arrangement and operation may be effected without departing from the spirit of the invention especially as defined in the appended claim.

What I claim is:

In a vehicle having a window well, a window movable in and out of said well to and from a closed position, an inside panel at the inner side of the well disposed out of parallelism to the plane of window travel, regulator mechanism for operating said window, said regulator mechanism comprising a window engaging arm, a pivotal mounting for one end of said arm disposed at substantially right angles to the plane of window travel, a gear sector for actuating said arm having a body portion substantially parallel to the plane of window travel, a pivotal mounting for said gear sector, the teeth of said sector being inclined laterally relative to said sector body portion and out of parallel relation to the plane of window travel, a driving pinion for said gear sector, said pinion being disposed intermediate the ends of a quadrant, having a lower end which is horizontal and passing through the axis of said pivotal mounting, and having an upper end which is vertical and passing through the axis of said pivotal mounting helical teeth on said driving pinion meshing with the sector teeth, those teeth of the pinion in engagement with the teeth of the sector being normal thereto, a shaft coaxial with said pinion disposed at substantially right angles to and projecting through the inside panel, said shaft inclining upwardly from said driving pinion, and a crank handle on said shaft on the inner side of the inside panel and rotatable in a plane parallel to the inside panel.
